UNITED STATES PATENT OFFICE.

LESTER WESTCOTT, OF THERESA, NEW YORK.

WRENCH.

1,193,326.

Specification of Letters Patent.

Patented Aug. 1, 1916.

Application filed November 9, 1915. Serial No. 60,537.

To all whom it may concern:

Be it known that I, LESTER WESTCOTT, a citizen of the United States, residing at Theresa, in the county of Jefferson and State 5 of New York, have invented certain new and useful Improvements in Wrenches, and I do hereby declare the following to be a full, clear, and exact description of the invention, such as will enable others skilled in the art 10 to which it appertains to make and use the same.

The object of this invention is to provide a novel type of wrench, for removing or replacing horseshoe calks, that will be of simple construction, cheap to manufacture, will be durable, and of such construction that it will accommodate any size or shape of shoe 15 calk, and can be conveniently associated with the calk.

Other objects will appear and be better understood in that embodiment of my invention of which the following is a specification, reference being had to the accompanying drawings forming a part thereof in 20 which:—

Figure 1 is a side elevation of the wrench. Fig. 2 is an edge elevation thereof showing the wrench end in section so as to disclose the operating base of one of the jaws. Fig. 30 3 is a transverse section taken on the line 3—3 of Fig. 1.

Referring to the drawings in detail, the numeral 1 designates the shank of the wrench, formed preferably of soft steel or 35 iron, and has its lower end provided with an opening 2, and its upper end provided with a frame 3. The frame 3 includes the upwardly converging side bars 4—4, and the upper connecting bar 5 which connects the 40 upper ends of the converging bars 4—4, as shown in Fig. 1 of the drawing. Associated with one of the sides 4 of the frame 3, is a stationary jaw 6. This stationary jaw is substantially U-shaped in cross section, and 45 has its sides lying on opposite sides of the adjacent sides 4 of the frame, and secured thereto by means of the pin 7 which extends through the sides of the jaw 6 and through the adjacent sides 4 of the frame. The outer 50 surface of the biting portion of the U-shaped

jaw 6 is provided with a series of upwardly extending teeth 8.

The opposite sides 4 of the frame 3, have slidably associated therewith a movable jaw 9. This movable jaw 9 is substantially 55 U-shaped in cross section and has its sides lying on opposite sides of the said adjacent sides 4 of the frame 3, and the outer ends of the sides of the jaw extend a distance beyond the sides 4 of the frame, as shown at 60 10, and a pin 11 extends through alined openings in the extended portions 10 of the sides of the jaw 9, and holds the jaw attached to the adjacent sides 4 of the frame. The biting portion of the U-shaped jaw 9 is disposed 65 inwardly of the frame and is provided with a series of downwardly projecting teeth 12. The sides of the jaw 9 are of greater length than the biting portions of the jaw 9, so as to provide the upper recess 13 and the lower 70 recess 14.

The jaws 6 and 9 are formed preferably of hard steel so as to admit of the same withstanding considerable strain.

In use, when it is desired to tighten a 75 calk in a horseshoe, the wrench is so positioned that the movable jaw thereon will be on the right side of the wrench. The movable jaw 9 is then moved in the direction of the shank 1, and the jaws 6 and 9 positioned 80 on opposite sides of the calk and the jaw 9 then moved forward so as to effect the gripping action between the calk and jaws 6 and 9, so that when the wrench is turned in the proper direction the calk will be tightened 85 in the shoe. When removing the calk from the shoe the wrench is turned so as to cause the movable jaw to be on the left side of the wrench and the calk then gripped between the jaws so that the same can be removed 90 when the wrench is turned in the proper direction.

Having thus described my invention what I claim as new is:—

A wrench of the class described comprising 95 a shank, a frame carried by one end of the shank and including a pair of side bars and an outer connecting end bar, a stationary jaw carried by one side of the frame and having a gripping surface disposed inwardly 100

of the frame, a movable jaw associated with the other side bar of the frame and being substantially U-shaped in cross section and having a gripping surface disposed inwardly of the frame, the sides of the movable jaw being arranged, respectively, on the opposite sides of the adjacent side bar of the frame and extending therebeyond, and a pin extending through the sides of the U-shaped

jaw and slidably engaging the outer edge of the adjacent side bar of the frame.

In testimony whereof I affix my signature in presence of two witnesses.

LESTER WESTCOTT.
